UNITED STATES PATENT OFFICE.

CHARLES M. GENTHNER, OF MIDDLETOWN, PENNSYLVANIA, ASSIGNOR TO WINCROFT STOVE WORKS, OF MIDDLETOWN, PENNSYLVANIA, A CORPORATION OF PENNSYLVANIA.

STOVE-SUPPORT.

1,051,099.

Specification of Letters Patent. Patented Jan. 21, 1913.

Application filed July 1, 1912. Serial No. 707,066.

To all whom it may concern:

Be it known that I, CHARLES M. GENTHNER, a citizen of the United States, and a resident of Middletown, in the county of 5 Dauphin and State of Pennsylvania, have invented certain new and useful Improvements in Stove-Supports, of which the following is a specification.

My invention relates to an improved stove 10 support made up of separate leg and skirt sections which are conveniently and neatly fastened together without the use of bolts.

The invention is fully described in connection with the accompanying drawings 15 and the novel features are specifically pointed out in the claims.

Figure 1 is an inside elevation showing a skirt and leg section fastened together. Fig. 2 is a similar view of the opposite 20 end of the skirt section alone. Fig. 3 shows an edge view of said skirt section. Fig. 4 is an outside view of the corner leg section indicating a skirt section secured to one side thereof.

25 The drawing shows but one corner leg section *b* and one skirting section *c*, but it will be readily understood that the use of a series of four of each is contemplated as indicated. The sections are tightly assembled 30 by merely dropping the skirt sections into locking engagement with the leg sections, the engaging parts being adapted to neatly draw together the respective meeting edges *b'* and *c'* thereof and the weight of the 35 stove when placed thereon serving only to more rigidly unite them; and the connected sections are conveniently held together for handling as a unitary structure, by means of removable retaining pins *d* as hereinafter 40 fully described.

Each corner leg section *b* is provided with similar upper and lower joint-lapping tongues, 10 and 10^a respectively, each lying inside of a meeting edge *b'* and having a top 45 locking notch 11 giving a U-shape thereto. The outer member 12 of the lower U-shaped tongue 10^a, as shown, has an upward extension which is provided on its outer skirt-contacting face 13 with a transverse groove 50 14 adapted to form in connection with a co-acting groove or clearance way 14^a in the opposing contacting face 15 of the assembled skirt, a passage-way for the retaining pin *d* previously mentioned. The locking notches 55 11 of the upper and lower tongues are ar-

ranged in a plane parallel with the vertical meeting edges, as shown, the two lower tongues on each leg however being spread apart farther than the upper ones to correspond with the outward-flare of the skirt. 60

Each skirt section *c* is provided with similar upper and lower locking lugs 20, lying in the same plane as the tongue notches 11 of the connected sections. They project inwardly from the contacting inner faces 15 of the skirt and are provided with bottom notches 21 giving them an inverted U-shape. The contacting faces of the locking-lugs 20 of the skirt and of the locking tongues of the legs being relatively tapered so as to draw 70 together the meeting edges *b'* and *c'* as adjacent sections are assembled. The skirt section is also provided with retaining-pin lugs 25 located above the lower notched locking lugs 20, and adapted to coöperate with the 75 grooved tongue in holding the inserted retaining pin *d* so as to prevent unintended disengagement of the combined sections.

In assembling the sections to form the stove-supporting structure, the skirt sections 80 are merely dropped into engagement with the leg sections, the weight of the former pressing the meeting edges of the sections together as the contacting faces of the skirt lugs 20 and leg tongues 10 come into close 85 contact. By inserting a retaining pin *d* at each joint the connection of the sections may be secured so as to enable free handling of the support as a unitary structure while at the same time permitting of the sections being 90 quickly disassembled when desired.

What I claim is:—

1. A stove support comprising leg sections each provided at each meeting edge with upper and lower joint-lapping tongues having 95 locking notches, and skirt sections each provided with inwardly projecting reversely notched lugs adapted to engage said tongues, the contacting faces of the engaging parts being tapered to draw together the meeting 100 edges of the sections.

2. A stove support comprising leg sections each provided at each meeting edge with upper and lower joint-lapping tongues having locking notches, and skirt sections each provided with inwardly projecting reversely notched lugs adapted to engage said tongues, contacting faces of the engaging parts being provided with registering retaining pins 105 ways substantially as set forth. 110

3. A stove support comprising leg sections each provided at each meeting edge with upper and lower joint-lapping tongues having locking notches, and skirt sections each provided with inwardly projecting reversely notched lugs adapted to engage said tongues and with adjacent retaining-pin lugs, contacting faces of the engaging parts being provided with retaining-pin-ways arranged

to coöperate with said retaining-pin lugs, 10 substantially as set forth.

In testimony whereof, I affix my signature, in the presence of two witnesses.

CHARLES M. GENTHNER.
